UNITED STATES PATENT OFFICE.

FRANCIS B. JOY AND CHRISTIAN H. VOGEL, OF DETROIT, MICHIGAN, ASSIGNORS TO THE DETROIT HEATING & LIGHTING COMPANY, OF DETROIT, MICHIGAN, A CORPORATION OF MICHIGAN.

DESIGN FOR A BUNSEN BURNER.

52,321.

Specification for Design.

Patented Aug. 27, 1918.

Application filed May 4, 1918. Serial No. 232,653. Term of patent 14 years.

To all whom it may concern:

Be it known that we, FRANCIS B. JOY and CHRISTIAN H. VOGEL, citizens of the United States of America, residing at Detroit, in the county of Wayne and State of Michigan, have invented a certain new, original, and ornamental Design for a Bunsen Burner, of which the following is a specification, reference being had therein to the accompanying

drawings, forming a part thereof, the view showing in perspective the improved design of burners.

We claim:

The ornamental design for a Bunsen burner, substantially as shown.

FRANCIS B. JOY.
CHRISTIAN H. VOGEL.
